(57) CLAIM

We claim the ornamental design for a percussion instrument, as shown and described.

DESCRIPTION

FIG. 1 is a perspective view of a percussion instrument, showing our new design;

FIG. 2 is a right-side elevational view thereof;

FIG. 3 is a left-side elevational view thereof;

FIG. 4 is a bottom plan view thereof;

FIG. 5 is a top plan view thereof;

FIG. 6 is a front elevational view thereof; and,

FIG. 7 is a rear elevational view thereof.

The remaining broken lines in FIGS. 1 and 6 represent the portions of the percussion instrument that form no part of the claimed design.
